UNITED STATES PATENT OFFICE

CHARLES J. ANCHOR, OF MILTON, PENNSYLVANIA, ASSIGNOR TO AMERICAN CAR AND FOUNDRY COMPANY, OF NEW YORK, N. Y., A CORPORATION OF NEW JERSEY

METHOD OF AND APPARATUS FOR FLANGING METAL

Application filed March 16, 1929. Serial No. 347,555.

This invention relates to a method of and apparatus for flanging metal, and has particular reference to flanging the side sheets of domes of car tanks.

A car tank is usually cylindrical and the dome is arranged on the top of the tank, the dome sheet being flanged along its lower edge in conformity with the contour of the tank. It will be apparent, therefore, that at the upper portion of the tank the flange must necessarily be at substantially right angles to the dome sheet at diametrically opposite points on the longitudinal center line of the tank, and the remainder of the flange will be at an obtuse angle, with respect to the side sheet, and in conformity with the contour of the tank. Heretofore dome sheets have been flanged in a suitable press to partially form the finished sheet, and then diametrically opposed portions of the flange have been hammered to define a right angle. Such a method is expensive and time consuming, and, therefore, one object of this invention is the provision of a method for mechanically forming the entire attaching flange of a dome sheet.

Another object of this invention is the provision of a method of mechanically flanging a dome sheet at one heating thereof.

A further object of the invention is the provision of means for mechanically forming the attaching flange of a dome sheet.

A still further object of the invention is the provision of means associated with a press for partially flanging diametrically opposed portions of a dome sheet, which means are removable after such partial flanging, whereby the press may be actuated to completely flange the dome sheet.

Other objects and advantages of this invention will be apparent from the following description taken in conjunction with the accompanying drawings in which:

Figure 1 is a side elevation of the apparatus for forming the side sheet, certain parts being shown in section and others being broken away;

Fig. 2 is a partial top plan view of the device, a portion thereof being on the line 2-2, Fig. 1, and another portion of the figure having parts broken away;

Fig. 3 is an end view of the male die member, showing a portion of the press head, and showing the initial formers in operative position;

Fig. 4 is a front view of the press, the female die member and die and the dome sheet being shown in section;

Fig. 5 is a detail view of the male die member showing the wedges or initial formers associated therewith; and

Fig. 6 is a sectional view of the female die holder with the female die therein, the work being shown in finished form.

In carrying out the present method an apparatus is provided which comprises broadly a furnace A in which a dome sheet blank is heated and a press B arranged adjacent the furnace and including a male die holder C, a female die holder D, a female die member E, and a male die member F.

The furnace A may assume any desired form, but, in the instance shown, is mounted on columns 2 and includes a heating flue 4 defined by firebricks 6; the upper edges of which are formed to the contour of the end of a cylindrical dome sheet blank to be flanged whereby to heat said end an even depth through the entire circumference of the sheet.

The furnace is arranged immediately over a hoist 8, which may be either hydraulic or pneumatic and which includes a ram 10 having a head 12, which includes spaced rails 14 connected at their ends by arcuate end plates 16, curved to conform to the contour of the dome sheet blank. Secured to the rails 14 adjacent the ends thereof are angles 18 adapted to engage the inner surface of the dome sheet to steady the same, as will be obvious from the description to follow.

A buggy 20 is provided which is substantially U-shaped and includes the sides 22 and an end sill 24, the buggy being mounted on wheels 26 travelling on rails 28 to a position over the hoist and carrying the dome sheet blank to be flanged to a position such that it may be engaged by the rails 14 of the ram head 12 when the latter is elevated; the ram lifting the blank so that the end to be flanged is extended into the heating flue 4 of the

furnace, as shown in Fig. 1. The dome sheet blank comprises a cylindrical structure having overlapped side edges riveted together, as shown clearly in Fig. 6 at 29. 5 Previous to forming the cylindrical structure, the blank has one end thereof formed to a predetermined shape, as indicated in Fig. 1; the form of the end of the blank being, of course, determined by the structure 10 to which it is to be attached, which, in the present instance, is a car tank of cylindrical form.

Arranged adjacent the furnace is the press B and, extending between the furnace and press and movable so as to be disengaged from the press, are spaced rails 30 which, when the blank is being heated, are so placed that one end of each thereof is supported on the female die holder D, as shown at 31 in 20 Figs. 1 and 2. Any form or desired type of rail support may be provided at the press, but, as illustrative of the invention, the rail supports shown in Fig. 1 include brackets 33 having an inverted T-shaped recess 35 formed therein which receives the rails 30. In the instance shown in the drawings, the rails merely rest on angles 32 secured to the columns 2 and may be easily moved over the angles 32, as shown clearly in full and dotted 30 lines in Fig. 2.

When the blank, which has been designated as 37, has been sufficiently heated in the furnace the ram 10 is lowered and the rails 30 arranged in such a position that the 35 blank is received on the rails, following which it may be moved thereover in any suitable manner into the female die holder D where it is supported on a spider 34 shown more clearly in Figs. 2, 4 and 6, and which 40 spider is mounted on the ram 36 of an air hoist 38.

The female die holder is mounted on a platen 40 which is vertically reciprocable by rams 42 of primary air hoists 43, and said 45 platen is preferably guided during reciprocation by vertical columns 44. Inasmuch as the specific type of hoist forms no part of the present invention, the same is not described in detail.

50 The columns 44 also support a press head 46 to which is secured the male die 48, the working surface 49 of which is formed complementary to the working surface of the female die 50 arranged in female die holder 55 D; the latter having an annular recess which supports the said die member 50, as clearly shown in the drawings.

It has been found in practice that if attempts are made to form the attaching 60 flange of the dome sheet at one operation, the metal of the sheet is so strained as to be liable to easy fracture, and, in fact, occasionally the metal is fractured or broken 65 during the flanging operation. This is due, it is believed, to the action of the die mem-

bers in forming the particular type of flange required for such articles as herein described. To obviate this, there have been provided suitable initial formers which, when the female die member is urged toward the male die member, engage the heated end of the dome sheet at diametrically opposite portions of the sheet to partially flange the latter, said flanging, of course, occurring at substantially diametrically opposed portions, said portions being those which, in the finished sheet, are at right angles with respect to the sheet.

These initial formers are clearly shown in the drawings and comprise segments 52 of substantially crescent shape, the upper surfaces of which are formed to the contour of the working surfaces 49 of the die member C and which, when in use, are adapted to engage said working surface, as shown in 80 Figs. 1 and 3. These formers are pivotally secured to brackets 54 secured to die member C and are each provided with a handle 56 for lifting them to inoperative position; the arms 58 extending from the segments having a cross bar 60 extending therebetween which is adapted to be engaged by a hook 62 secured to the head 46 whereby to suspend said formers, as shown in Figs. 3, 4 and 5.

These formers 52 are of a length sufficient to give a gradual taper from their centers to their extremities, and are beveled in cross section whereby to partially or initially flange the dome sheet, as shown in Fig. 1, after which the die members are separated and the formers withdrawn, whereupon the die members are brought together again and the sheet is then flanged throughout its entire circumference to its desired form; those portions which have been initially flanged being further flanged at right angles with respect to the sheet on the longitudinal center line of the tank, as clearly shown in Fig. 4, the right angled flange portions merging into the remainder of the flanged edge of the dome sheet, and the completed flanged end conforming to the contour of the tank to which the dome sheet is to be attached.

Following the completion of the flanging, the primary air hoists are actuated to lower the platen 40 to separate the male and female die members, and then the ram 36 of hoist 38 is actuated to elevate the kicker to lift the flanged dome sheet blank, and it may then be removed from the female die member.

The new and improved method of forming the sheet includes first heating the end of a dome sheet and then transferring said sheet to a press while in its heated condition. The press is then actuated to flange the sheet at diametrically opposite portions only and then, without further heating, the sheet is flanged completely around the circumference at the end thereof. It is to be noted that diametri-

cally opposed portions of the sheet are subjected to two pressing operations which, it has been found, results in a construction in which the metal at the end of a dome sheet 5 is not strained to excess, and, consequently, an unfractured flange is formed, which flange possesses the required strength.

From the above description, it is believed that the construction and operation of the apparatus just described will be fully apparent to those skilled in the art, but it is not to be understood that the invention is limited to the specific details of disclosure as shown in the drawings, as the drawings are for illustrative purposes only, and various changes in the form and proportions of the apparatus may be made within the scope of the appended claims. The method specifically recited herein is, of course, susceptible of modification, and it is not to be understood that the applicant is limited to the specific method outlined herein, as obviously various changes may be made within the scope of the appended claims without departing from the 25 spirit of the invention.

What is claimed is:

1. In a press, initial formers adapted to be interposed between the die members thereof for initially acting on the work at spaced predetermined portions only, said formers being removable to inoperative position to permit normal action of the die members.

2. In a press, die members for flanging the entire circumference of cylindrical work, and means adapted to be positioned between the members for preventing combined action of the die members and for initially acting on the work at spaced predetermined portions only.

3. In a press, die members for flanging the entire circumference of cylindrical work, and means adapted to be positioned between the members for preventing combined action of the die members and for initially acting on the work at spaced predetermined portions only, said means being movable to inoperative position after initial action to permit the die members to act upon the entire circumference of the work.

4. In a press, male and female die members, and means for initially acting on work in said press prior to the combined action of said die members comprising circumferentially formers carried by the male die member and adapted to be interposed between said members for acting on the work at predetermined points, said formers being removable to permit action of the die members on the work including those portions previously formed.

5. In a press, male and female die members, and formers pivotally secured to one of said members and having one face complementary to the working face of the die member to which it is attached, said formers being so

formed as to initially shape predetermined portions only of the work and being removable from between said members to permit complete action of the die members.

6. In a press, male and female die members for flanging a tank dome sheet, formers secured to the male die member and adapted to be positioned between the die members for forming flanges at diametrically opposite points on the dome sheet, said formers being removable from between the die members whereby to permit action of the die members on the entire circumference of the sheet to flange the latter.

7. In a press for flanging dome sheets, male and female die members adapted to flange the entire circumference at one end of a dome sheet, and initial formers connected to the male die member and adapted to be positioned against the working face thereof for partially flanging the dome sheet at predetermined points and less than the entire circumference of the sheet, said formers being removable to inoperative position after partial flanging of the sheet whereby the male and female die members completely flange the sheet.

8. In a press for flanging dome sheets, male and female die members for flanging the entire circumference of the sheet, and initial formers adapted to be positioned between said die members for partially flanging said sheet at diametrically opposite points only prior to complete flanging by said die members.

9. A press comprising male and female die members adapted normally for flanging the entire circumference of a tank dome sheet and means for initially flanging spaced predetermined portions only of the sheet comprising formers adapted to engage the working surface of the male die member whereby to partially flange the dome sheet, said formers being removable to inoperative position to permit action of the male and female die members around the entire circumference of the dome sheet including the previously formed flange portions.

10. The method of forming tank dome sheets which comprises forming a cylindrical structure, heating one end thereof, pressing predetermined portions only of the heated end to form flanges, and finally subjecting the entire circumference of the heated and partially flanged end to pressure to further flange the previously flanged portions and to form a continuous flange at the said heated end.

11. The method of flanging tank dome sheets which includes heating one end of a dome sheet and then subjecting said heated end to at least two pressings one of which flanges diametrically opposite portions only and the other of which flanges the entire

circumference of the heated end including the previously flanged portions.

12. The method of flanging tank dome sheets in a press which comprises placing spaced formers in the press, actuating the press to flange spaced predetermined portions only of the dome sheet, removing the formers and finally actuating the press to bend the entire circumference of the sheet, including the previously flanged portions.

13. The method of forming tank dome sheets which comprises heating one end of a cylindrical metallic structure, flanging diametrically opposed portions only of the heated end of the sheet, and then without further heating flanging the entire circumference of the said heated end.

14. The method of forming tank dome sheets which comprises heating one end of a cylindrical metallic structure, then bending diametrically opposed portions of said heated end to partially flange the same, and then subjecting the entire circumference of said heated end to pressure to further bend the previously bent portions and to form flanges merging with the said previously bent portions.

In witness whereof I have hereunto set my hand.

CHARLES J. ANCHOR.
